WINDOW CONSTRUCTION COMPRISING RADIATOR HOUSING

Application filed February 7, 1929. Serial No. 338,150.

It has been recognized for many years that radiators are unsightly, and even when covered by an enclosure, they are very much in the way. The most advantageous place for a radiator is near a window, and it has long been recognized that some method should be evolved whereby the radiator could be built into the wall under the window. Ordinarily, however, this is not feasible because the window-frames are set in well toward the inside of the wall to show the proper architectural reveal on the outside of the building, and the principal weight of the window-frame is well in from the outside edge of the sill. This demands that the window-frame be supported directly in the masonry wall, leaving little or no space to recess the radiator under the window.

The present invention overcomes this difficulty and actually strengthens the window-frame and the firmness of its support and at the same time produces a combined window-frame and radiator housing which can be economically constructed and installed and which will permit the use of an enclosed radiator taking up very little space and which permits of ready access for making the necessary steam connections.

To accomplish this result, the wall below the window opening is formed with a recess on the inside which should be of substantial vertical depth but should be so built that the shelf forming the bottom of the recess should be a considerable distance above the floor; for example, in an ordinary 12-inch wall this recess may extend into the wall about 4 inches and be from 8 to 12 inches deep vertically, leaving a space of the order of about 20 inches between the floor and the bottom of such recess. A sill member is provided to cover this recess and this member is so shaped that it will extend both out over the wall beyond the recess and into the room well beyond the line of the wall. Such sill member may be formed in one piece or made of two or more pieces as desired. While this sill member may be supported at its ends, it will have very little bearing surface on the wall, for one must remember that a space has to be left

under the outside edge of this sill member for caulking.

In order to support and stiffen this sill member a second sill member is provided which preferably is in the form of a box-like structure with a bottom which will substantially cover the shelf which forms the bottom of the recess, a back which will extend up to meet the upper sill member and sides which extend into the room substantially as far as the upper sill member and which serve to stiffen the whole structure and also support the inner edge of the upper member. The box-like structure described is preferably firmly attached to the upper sill member as by welding, so that the whole sill becomes a substantially integral truss-like structure. However, even if the lower member is not welded to the upper one, the two will cooperate to give a particularly strong and firm support for the window-frame (for it will be supported on the wall across its entire width) and yet a space of substantial size will be provided in which a radiator may be housed. In a structure of this type it is intended that the radiator will extend into the room beyond the line of the wall and substantially as far as the sides of the box-like member, but inasmuch as the radiator will be supported on brackets carried by one of the sill members and thereby attached directly to the window-frame, the radiator will be firmly held against any leverage action tending to pull it into the room.

A front cover plate will ordinarily be provided which will run down from the upper sill member and connect the inside edges of the two sides of the box. As these sides extend into the room well beyond the line of the wall (as for example a distance of 3 or 4 inches) while the bottom should only cover the bottom of the recess, a space will be provided between the lower edge of the cover plate and the face of the wall through which cold air may enter the radiator box. An outlet for the heated air may be made by perforating the upper sill or forming perforations in the upper part of the front cover plate, or both.

Ordinarily radiators are located quite close to the floor, which means that the cold air to be heated must be drawn in at right angles to its final direction of flow. This change of direction in the path of the cold air flow interferes with its movement to a surprising degree, and in order to overcome the inertia of the air, wall radiators are ordinarily made much higher than they are thick so that an efficient flue action is obtained to supply the necessary pull to draw in cold air. We have found that where the radiator is located well above the floor as described, and a path is provided so that the air can flow directly upward to the radiator, no such extended flue action is necessary, and we have further found that once the cold air is drawn into the box, it will spread out in the box, and can be deflected out through the front of the box with a very little loss of velocity. While it is within the spirit of our invention to have the heat escape through perforations in the upper sill member, we have found that with the construction described, this is not necessary, but on the contrary is undesirable as the upper sill member will become so hot that contact with it may be quite painful. Where the air goes out through perforations in the front panel, such panel will tend to be heated, but if the upper sill member is formed with an overhanging flange, accidental contact with the front panel is not likely to occur, and in such case heating the front panel will increase the efficiency of the radiator by transmitting heat to the room by radiation as well as by convection.

As the space arranged for housing the radiator is quite small, it is desirable to use a fin type radiator which may be heated in any desired way as by steam or electricity. By using a radiator of this type and by arranging for the direct vertical air inlet that has been described, we find that a radiator with the necessary heating efficiency can readily be installed in the space available for a window of ordinary proportions.

Inasmuch as the radiator housing is formed as an integral part of the window-frame, the radiator and necessary valves can all be installed at the factory, and since the housing must be made sufficiently strong to support the weight of the window-frame, this housing will protect the rather delicate fins of the radiator from being bent during shipment and installation (a danger which is one of the real drawbacks to the use of radiators of this type). After the window, including the radiator, is installed, the steam pipes may be readily connected either by bringing them up on the face of the wall so that they pass through the space immediately behind the front cover plate, or if preferred, holes may be formed in the bottom of the box and the steam pipes may be brought up in chases

formed in the walls. In either case, the recess will supply adequate space to permit the pipes to be readily connected to the radiators.

For the purposes of illustration, we show in the accompanying drawings, an example of our invention as applied to a double-hung window-frame. In these drawings, Fig. 1 is a section through a portion of a wall and sill of a window; Fig. 2 is a front elevation of the lower portion of a window with parts of the front cover plate broken away; Fig. 3 is a horizontal section taken on line 3-3 of Fig. 2, and Figs. 4 and 5 are horizontal sectional views showing a method of assembling a fin radiator of the type which we may use.

In the illustrative example here shown the wall 10 is indicated as the usual 12" brick wall, with the masonry sill formed of a row of bricks 12 turned up on edge. A recess having a horizontal depth equal to the width of one brick and a vertical depth slightly greater than the thickness of 4 bricks is formed on the inside of the wall. Resting on the shelf 13 which forms the bottom of this recess is a plate 14 which forms the bottom of a box-like structure having a back 16 and sides 18. In the example here shown the back 16 and sides 18 are formed of one piece of metal and the bottom 14 has one side and its ends turned up and welded to the sides of the box. It is to be noted that the bottom member 14 is of sufficient width substantially to cover the ledge at the bottom of the masonry recess and also may be made to overhang the plaster facing 20 but does not extend substantially beyond the face of the wall whereas the sides 18 extend out a substantial distance beyond the face of the plaster 20.

Above the box-like structure just described, is an upper sill member 22 which has a flat portion extending into the room slightly further than the sides 18 and provided with a downwardly depending flange 24. The portion 26 is bent down and inwardly to make a seat for the lower sash 28 and the portion 30 extends out and partly covers the bricks 12. In this example these parts are all formed in one piece but as pointed out above they may be made in two or more sections bolted or united together. The usual space is left between the portion 30 and the bricks 12 which is filled with caulking 32.

In the present embodiment the back 16 of the box structure is bent outwardly at 34 and welded to the portion 26 of the upper sill member. The side members 18 have their upper portions bent over as indicated at 36 in Fig. 2 and are welded on the underside of the sill member 22. By this construction the sill member 22 and the box-like structure are united to form a rigid integral whole which rests directly on the masonry shelf 13 at the bottom of the recess formed in the wall. Connected to the upper sill member 22 in any

usual way are the jambs 38 which of course are anchored in the wall. While the bottom of the jambs 38 may be partly supported in the masonry, it is obvious from Fig. 1 that the window-frame is primarily carried by the box-like member which rests on the shelf 13.

5 Welded to member 14 are two brackets 40 to support pipes 42 of the radiator. The brackets 40 each carry a pivoted bar 44 adapted to be bolted down as indicated at 46 to hold the radiator firmly in place in the structure. A front cover plate 48 is attached by screws 50 (see Fig. 3) to the sides 18, leaving a gap between the lower edge of the cover plate 48 and bottom member 14. As has already been pointed out, it is preferable to have the heated air pass out through the cover plate 48. Accordingly, there is supplied a deflector 54 in the box, and openings 56 in the upper portion of the cover plate. 10 If desired, insulation 58 may be placed underneath the sill member 22 so that the latter will not become too hot.

15 The radiator here illustrated comprises the two pipes 42 which are united together at their ends by headers 60 and 62. A main control valve 64 is connected to header 60 and is supplied with a control handle 66 attached to a stem 68 which passes up through sill member 22. The valve 64 is provided with a union 70 for the ready connection to a steam inlet pipe 72 which is here shown as brought up along the face of the wall. A drip valve 74 is connected to header 62 and is provided with a union 76 for ready connection to the return pipe 78.

20 Mounted on the pipes 42 are a series of fins 80 which are preferably formed in the general shape shown in Fig. 1, for we have found that having these plates extend back into the lower corner of the box gives the maximum efficiency for the minimum amount of metal used in the fins. This is of some importance commercially, for the fins 80 and pipes 42 are preferably formed of a metal having a relatively high factor of heat conductivity such as copper. The vertical edges of the fins 80 are preferably bent over as indicated in Figs. 4 and 5 so that these fins 25 will be kept properly spaced and not bent together by accidental contacts.

25 It is important that the fins 80 make very close contact with the pipe 42. One method of combining the fins and pipes is illustrated in Figs. 4 and 5. According to this method, each fin 80 is formed with a hole the size of a pipe 42 and around this hole is formed a corrugated groove 82. A stop ring 84 is screwed on one end of each pipe 42, and a fin 30 80 is then passed over the two pipes with the convex side of the groove 82 against the stop ring 84. A collar 86 having its corner cut away is then slipped over each pipe 42 and compressed toward stop ring 84. This 35 flattens out the groove 82 contracting the

metal of fins 80 about the pipe 42 and catching the edge of this metal under the cut-off corner of collar 86. A second fin 80 is then fitted to the pipes, another pair of collars 86 put on and the operation continued until the entire number of fins is in place. The headers 60 and 62 are then connected, and the radiator is complete. If preferred, the grooves 82 may be flattened out by an appropriate tool and the collars 86 pressed on after each such flattening is accomplished.

30 As a radiator of this type is very susceptible to damage, it is advisable to attach the valves and unions in the shop and anchor the radiator in place in its box by the bars 44. Since the box comprising the bottom 14 and the back 16 and sides 18 must be made heavy enough to support the window, these members will protect the radiator both during shipment and installation. Once the window 35 is installed, it is a very simple matter for the steam-fitter to connect the risers to the unions, so that a minimum of field labor will be necessary.

35 It is to be understood that the example given is by way of illustration only, and may be modified in many particulars without departing from the spirit of the invention.

40 What we claim is:

1. In combination with a wall having a window opening and a recess in the inside of the wall below such opening, a sill member adapted to cover said recess and extend both out over the wall beyond said recess and into the room beyond the face of the wall, and a second sill member below said first sill member rigidly connected with said first sill member and extending down to the bottom of said recess and resting on the wall, whereby the window-frame is supported on the wall and a recess is provided under the upper sill member for housing a radiator.

45 100 105 110 115 120 125 130

2. In combination with a wall having a window opening and a recess in the inside of the wall below said opening, a radiator housing in said recess resting on the bottom thereof comprising a bottom extending in not substantially beyond the face of the wall below such recess and side members which do extend in substantially beyond the face of the wall below such recess, a sill member comprising part of a window-frame resting on and rigidly connected with the sides of said housing covering said recess and extending out beyond the recess and in beyond the side members of the housing, and a removable cover-plate for the front of the housing.

50 55 60 65 70 75 80 85 90 95 100 105 110 115 120 125 130

3. In combination with a metal window-frame, a sheet metal radiator enclosure adapted to support a radiator, said enclosure having an upper portion adapted to serve as a portion of the sill of the window-frame, a bottom, and sides rigidly connecting said bottom to said upper portion, whereby said enclosure is adapted to support said window-

frame in a wall across substantially its entire width, an air outlet near the top of said enclosure and an air inlet at the bottom thereof for admitting air from the room side of the window, and a removable front cover plate therefor.

4. In a metal window-frame construction, two horizontal sill members rigidly connected together with a substantial space between them, whereby a rigid base is obtained for the window-frame and a space is provided in which a radiator can be housed, a removable cover-plate for the front of such space, a lower inlet at the bottom of such space for admitting air from the room and an upper outlet for heated air to escape from such space into the room.
